[57] CLAIM

The ornamental design for hand loop for jeans, as shown and described.

DESCRIPTION

FIG. 1 is a left side view of hand loop for jeans showing my new design.

FIG. 2 is a front view thereof.

FIG. 3 is a rear view thereof.

FIG. 4 is a top view thereof. The bottom view thereof would be a mirror image of FIG. 4.

The jeans shown in broken line are for illustrative purposes only.

FIG. 1

FIG. 4
